UNITED STATES PATENT OFFICE.

JOHN ALFONZO WESENER, OF CHICAGO, ILLINOIS.

APPARATUS FOR TREATING FLOUR.

1,099,225.

Specification of Letters Patent.

Patented June 9, 1914.

Application filed March 6, 1913. Serial No. 752,400.

To all whom it may concern:

Be it known that I, JOHN A. WESENER, a citizen of the United States, residing at Chicago, in the county of Cook and State of Illinois, have invented certain new and useful Improvements in Apparatus for Treating Flour, of which the following is a specification.

My invention relates to the treatment of flour for the purpose of maturing the same, improving its quality and condition, and removing the color therefrom; and the primary object of the invention is to provide a form of apparatus for accomplishing these results more efficiently, conveniently and economically than has been heretofore possible.

A further object is to provide an apparatus for treating flour which will reduce to a minimum the amount of knowledge and skill required for carrying out the treatment and thereby reducing the cost of the process and insuring a better and more uniform product.

A further object is to provide an apparatus of this sort which will be compact and inexpensive in its construction.

A further specific object of the invention is to provide an improved form of apparatus for practising the processes disclosed and claimed in Patent No. 803,684 granted to me August 20, 1907, and in my co-pending application Serial No. 749,493, filed February 19, 1913, patented September 2, 1913, as Patent No. 1,071,977.

I have discovered, after very considerable experience in the treatment of flour with gases, particularly chlorin gas or a mixture of nitrosyl chlorid gas and chlorin, that in order to obtain the best results (and in fact in order to obtain any satisfactory results when chlorin, bromin or other similar gases are employed) it is necessary, in the first place, to regulate quite accurately the amount of the agent which is used for the treatment of a flour of a given quantity and character and, in the second place, that the gas should be as nearly anhydrous as possible. The latter requirement is contrary to the common teaching of this art which heretofore has proceeded upon the assumption that the reactions taking place are in the nature of oxidation processes, and the importance of the former requirement has not been properly appreciated for a similar reason. For example, it was proposed to "bleach" flour by subjecting it to treatment

by chlorin gas produced by electrolysis. This method could not succeed because when chlorin gas is generated electrically (and the same will be true if it were generated by any of the ordinary chemical means and used immediately as generated) it necessarily will contain a considerable amount of moisture and will also contain impurities and be produced in such varying amounts as to make accurate regulation in its application to the flour impossible. On the oxidation theory moisture was of course essential to the desired reaction and therefore the suggested method of producing the gas appeared wholly unobjectionable. I am convinced, however, that oxidation instead of being sought for is to be avoided as far as possible as its effects are deleterious rather than advantageous. The reasons for this are fully set forth in my co-pending application Serial No. 749,493 (patented September 2, 1913, as Patent No. 1,071,977), and need not be repeated here. Suffice it to say that it is quite possible to get excellent results by the use of chlorin gas alone if the gas is applied to the flour in an anhydrous condition and in the proper amounts. The amount of gas used will vary with the character of the flour treated. If the wheat from which the flour is made is a hard wheat, such as spring wheat, and contains a relatively large amount of gluten, it will require more gas than a softer winter wheat. The amount of gas to be used should not substantially exceed one pound of the liquefied gas to five thousand pounds of flour and should not ordinarily be less than one pound of the liquefied chlorin to ten thousand pounds of flour.

A preferred embodiment of my invention is shown in the accompanying drawings wherein—

Figure 1 is a side elevation of the apparatus with certain parts broken away; and Fig. 2, a plan view of the same.

Like characters of reference designate like parts in the several figures of the drawings.

Referring to the drawings, A designates a treating cell or chamber, B, B tanks adapted to contain a liquefied anhydrous gas or mixture of gases, such, for example, as chlorin, or a mixture of chlorin and nitrosyl chlorid gas.

C designates a gas manifold with which the tanks B, B are connected, D a cabinet

through which the gas in the manifold passes and which contains certain other devices to be hereinafter described, E a blower, F, F air pipes, one leading from the blower to the treating chamber A and the other to another treating chamber (not shown), G, G gas pipes connected with the manifold C and leading respectively to the treating chambers A, and H a pressure gage 10 connected with the gas manifold. Flour enters the treating chamber at the top through a pipe 25 and falls through a series of conical funnels 26. It is kept in agitation by means of disks 27 on a shaft 28 which is rotated by any suitable driving mechanism. I have shown a bevel gear 29 on the upper end of the shaft which is meshed by a bevel gear 30 on a shaft 31 provided with a belt pulley 32. Preferably the 15 shaft 28 is provided with scrapers 33 which operate against the inner surfaces of the funnels 26. The apparatus may comprise any number of treating chambers such as that described. The drawings show the connections for a second treating chamber. The second chamber itself is not shown and will not be further adverted to.

The gas manifold C has connections for two gas supply tanks B, B, in order that 20 when one tank is emptied the other may be opened up and the first one removed and re-filled without interrupting the continuous operation of the apparatus. Each tank B is connected with the manifold by a pipe 34 25 and valve 35 of suitable construction. Each tank B is preferably provided with a similarly constructed valve designated in the drawings 35^a.

Interposed between the gas manifold and 30 each of the gas pipes G is a valve designated as a whole, 46 and manipulated by a hand wheel 62 which is constructed so as to be capable of very minute adjustment to enable the flow of gas to the treating chamber to 45 be given a close and accurate régulation.

Preferably a reservoir or pressure chamber 64 is interposed between the valve 46 and the pipe G which leads to the treating chamber, a short pipe 65 leading from the 50 valve to the chamber, the purpose of this being to insure a uniform delivery of gas to the flour.

The purpose of the pressure gage H is primarily to indicate the exhaustion of the 55 gas from the tank B. It also enables the operator to test the rate of flow past valve 46 and therefore the amount of gas going to the treating chamber. This can be done by shutting off the connection between the supply tank B and the gas manifold and observing the rapidity with which the indicating hand of the gage returns to zero.

The blower or fan E may be of any desired type. It delivers into an air trunk 74 65 with which the pipes F, F are connected.

The pipes F, F may be preferably provided with the shut-off valves 75.

An important feature of my apparatus is that the air and gas are mixed at the point of entry of the gas into the treating chamber. Moreover, the arrangement is such that with a stoppage of the blower the gas cannot readily back up through the air pipe and corrode it and the blower. The gas and air are mixed by means of a mixing device consisting of an air nozzle 76 connected with the pipe F and formed with a downwardly extending bend 77 which enters the side of the treating chamber, and of a gas nozzle 78 connected with the gas pipe G, the extremity 79 of which is bent to correspond with the bend in the air nozzle and which extends into the latter. The stream of gas is therefore surrounded by a stream of air and this results in a complete and thorough mixing of the air and gas. The downward inclination of the lower end of the gas nozzle prevents the gas from backing up into the air pipe, in case the blower is shut down, since chlorin gas is considerably heavier than air. The pressure in the tank B, which averages about one hundred and twenty-five pounds per square inch, is reduced by the valve 46 so that the pressure in pipe F is just a trifle above atmospheric pressure. 95 This is necessary in order that the supply of gas to the flour should not be too rapid. The constant suction of the air on the gas nozzle 79 tends to draw the gas out through the gas nozzle 79. Uniformity of flow of the 100 gas is insured by the supply of the gas in the reservoir. The flour in the treating chamber A is kept in constant agitation so that every particle of it comes into contact with the mixture of air and gas delivered 105 by the nozzle 77, 79.

While I have described my invention in a certain preferred form of apparatus, it will be understood that modifications might be made therein without departure from the 110 invention.

I claim:

1. In apparatus for maturing and bleaching flour by means of an agent which is an active gas at atmospheric pressure and ordinary temperatures, the combination with a treating chamber, of a container adapted to hold a stored quantity of the agent in liquefied form, a conduit leading from the container to said treating chamber provided with controlling apparatus for introducing the agent into the treating chamber in gaseous form and in regulatable quantities, and means for mixing the air with the gas within the chamber but before it comes into 120 contact with the flour.

2. In apparatus for maturing and bleaching flour by means of an agent which is an active gas at atmospheric pressure and ordinary temperatures, the combination with 130

a treating chamber, of a container adapted to hold a stored quantity of the agent in liquefied form, a conduit leading from the container to the treating chamber provided 5 with controlling apparatus for introducing the agent into said treating chamber in a regulatable stream, and means for directing a stream of air against the gas stream within said chamber which breaks up the gas stream 10 and dilutes the gas with air before it comes into contact with the flour.

3. In apparatus for maturing and bleaching flour by means of an agent which is an active gas at atmospheric pressure and ordinary 15 temperatures, the combination with a treating chamber, of a container adapted to hold a stored quantity of the agent in liquefied form, a pipe leading from the container to the treating chamber provided with controlling 20 apparatus for introducing the agent into said treating chamber in a regulatable stream, a blower, and an air pipe leading from the blower into the treating chamber, the end of which air pipe surrounds the 25 end of said gas pipe.

4. In apparatus for maturing and bleaching flour by means of a gaseous agent, the combination with a treating chamber, of a source of supply of gas, a gas pipe leading from said source of supply into the treating 30 chamber, a blower, and an air pipe leading from the blower into said treating chamber, the end of which surrounds the end of said gas pipe.

5. In apparatus for maturing and bleaching flour by means of a gaseous agent heavier than air, the combination with a treating chamber, of a source of supply of gas, a gas pipe leading from said source of supply into the treating chamber, a blower, and an air 40 pipe leading from the blower into said treating chamber, the end of which surrounds the end of said gas pipe, the ends of both pipes having a downward inclination, for the purpose described.

JOHN ALFONZO WESENER.
